UNITED STATES PATENT OFFICE.

EDOUARD BRANLY AND HENRY LAURENT, OF PARIS, FRANCE.

SAFETY-SCREEN FOR SAFES AND STRONG-ROOMS.

No. 926,385.

Specification of Letters Patent. Patented June 29, 1909.

Application filed July 9, 1908. Serial No. 442,712.

To all whom it may concern:

Be it known that we, EDOUARD BRANLY and HENRY LAURENT, citizens of the Republic of France, residing, respectively, at 21 Avenue de Tourville, Paris, and 15 Rue Boccador, Paris, in the Republic of France, have invented certain new and useful Improvements in Safety-Screens for Safes and Strong-Rooms, of which the following is a specification.

This invention relates to safety-screen devices for safes or strong boxes and strong rooms based on the application of the known principle consisting of using hollow plating 15 filled with compressed air and communicating with a manometer the movable part of which closes an electric circuit and produces an alarm signal, when the pressure falls by reason of the perforation of the plating at 20 any part.

The invention has for its principal object to provide simple constructions for such purpose as hereinafter described enabling the said screens to be applied in a practical manner to safes and strong rooms; and it further relates to additional security devices which will be indicated in the description.

In the annexed drawings Figures 1 and 2 show a strong room provided with a screen 30 according to the invention, Fig. 1 being a vertical section on the line A—B of Fig. 2 and Fig. 2 a horizontal section on the broken line C D E F of Fig. 1. Fig. 3 shows in horizontal section to enlarged scale a safety device 35 applicable to the locks of the doors of safes or strong rooms according to my invention. Figs. 4 and 5 show diagrammatically in horizontal and vertical section respectively a strong room fitted with an internal 40 screen according to the invention. Fig. 6 shows diagrammatically a strong room with a screen or shutter partly inside and partly outside.

Referring to Figs. 1 and 2 it will be seen 45 that the protecting device for a safe is composed of a hollow shutter formed of two parallel sheets of steel, 6, 7, surrounding the safe on all its vertical sides except in front of the door. The hollow panel thus constituted is 50 placed between the usual outer steel shutter 8 and the inner refractory lining 9 and is connected with the upper and lower horizontal panels, countersunk into the refractory lining by means of a suitable number of tubes 10, 11. 55 The upper panel is provided with an opening 12 closed by a plate 13 fixed to the upper

shutter 14 having the object of producing an escape of air if the top of the safe is raised.

The door of the safe is provided with a separate panel 15 placed between the outer steel door and the refractory lining; communication between the panel of the door and the other covering panels is insured by a known connection comprising a junction piece 16 fixed at the end of the bent tube 17 entering 65 the panel 15, the said tube 17 being pushed by the action of a spring 18 against an outlet connection 19 secured in the frame of the door and located at the end of the tube 20.

It will be seen that a safe provided with a 70 covering such as has been described cannot be attacked at any point without an immediate escape of the compressed air contained in the cover; communication between the covering and a manometer indicator of a 75 known type such as indicated at M is established by means of the tube 21 sealed in the wall and passing through the wall of the safe to the interior of a sealing socket 22, which gives it the appearance of a sealing bolt. By 80 means of the wires X X the manometer M is 85 in electrical connection with a suitable alarm signal (not shown).

In order to protect rooms and safes against a person in possession of keys, who, by rapidly opening the door might stop up the outlet 85 19 and prevent the indicating apparatus from operating, the locks of the rooms and the safes are provided with a security device shown in Fig. 3.

It is known that the opening of safety locks is effected in three successive operations: 1st. Opening of the controlling or securing lock. 2d. Opening the principal lock. 3d. Opening the lock-bolts by means 95 of a handle.

It suffices that the air under pressure should escape during the opening of the securing lock since for opening the door it is necessary to effect the two other operations 100 which takes a length of time sufficient for the operation of the indicating apparatus.

In the arrangement shown in Fig. 3, a valve 23 is kept closed by a spring 24 and opens when, during the opening of the securing 105 lock, the bolt 25 passes from z to z¹.

From Figs. 4 to 6 it will be seen that the shutter for strong rooms is composed of the hollow panels 26 formed by two parallel walls of sheet steel and corresponding to each 110 of the walls of the room. The said hollow panels are held together by means of double

headed joint covers 27 for the walls and double corner brackets 28 for the angles. The atmospheric communication of the different panels is assured by means of tubulures connected by junction tubes.

29 represents the junction of the two juxtaposed panels. 30 the junction of the two angle panels. 31 the junction of a vertical panel with a horizontal panel protecting the 10 ceiling or the floor.

The door is protected by a hollow panel 32 similar to the wall panels, placed between the outer steel shutter and the refractory lining and communicating with the said wall panels 15 by means of a joint like that previously described and a tubulure 33.

In the case where the inside of the chamber to be covered is not clear, as for example the walls of strong rooms provided with 20 safes, location cases, shelves, the protecting panels 34 will be placed outside as indicated in Fig. 6, the said panels 34 being attached to the interior panels by means of tubulures 35.

The door will be provided with a safety device described with reference to the safe.

Having now described our invention, what we claim as new and desire to secure by Letters Patent is:

1. A safety screen arrangement for safes 30 and strong rooms comprising in combination hollow panels formed of two parallel sheets of metal surrounding the safe on all its sides and placed between the usual outer steel shutter and the inner refractory lining, tubes 35 connecting said hollow panels one with each

other except with the panel of the door, a flexible joint connection adapted to establish communication between the panel of the door and the other panels, a plate secured to the upper shutter and closing a hole formed 40 in the upper panel, and a manometer indicator communicating with the hollow panels, substantially as described and for the purpose set forth.

2. A safety screen arrangement for safes 45 and strong rooms comprising in combination hollow panels formed of two parallel sheets of metal surrounding the safe on all its sides and placed between the usual outer steel shutter and the inner refractory lining, tubes 50 connecting said hollow panels one with each other except with the panel of the door, a flexible joint connection adapted to establish communication between the panel of the door and the other panels, a valve device 55 closing a tubulure formed on the panel of the door, a bolt adapted to open said valve device by pressure when the key of the safety lock opens the securing lock, and a manometer indicator communicating with the hollow 60 panels, substantially as described and for the purpose set forth.

In testimony whereof we have affixed our signatures in presence of two witnesses.

EDOUARD BRANLY.
HENRY LAURENT.
